CONTROL LEVER FOR AEROSOL CONTAINERS

Clarence E. Stow, Kansas City, Mo.

Application October 21, 1958, Serial No. 53,055

Term of patent 14 years

(Cl. D62—2)

Fig. 2.

Fig. 3.

Fig. 1.

Fig. 4.

Fig. 5.

Fig. 1 is a top perspective view of a control lever for aerosol containers, showing my new design;

Fig. 2 is a rear elevational view thereof;

Fig. 3 is a side elevational view thereof taken from the left of Fig. 2, with a conventional aerosol container shown in broken lines for illustrative purposes only; and

Figs. 4 and 5 are top and bottom plan views respectively of the control lever for aerosol containers.

I claim:

The ornamental design for a control lever for aerosol containers, as shown.
